(57) **CLAIM**

The ornamental design for a growing enclosure, as shown and described.

DESCRIPTION

FIG. 1 is a top perspective view of a growing enclosure showing our new design;

FIG. 2 is a bottom perspective view thereof;

FIG. 3 is a side view thereof;

FIG. 4 is a top view thereof;

FIG. 5 is a bottom view thereof;

FIG. 6 is another top perspective view thereof;

FIG. 7 is another bottom perspective thereof;

FIG. 8 is another side view thereof;

FIG. 9 is another top view thereof;

FIG. 10 is another bottom view thereof;

FIG. 11 is another top perspective view thereof;

FIG. 12 is another bottom perspective view thereof;

FIG. 13 is another side view thereof;

FIG. 14 is another top view thereof; and,

FIG. 15 is another bottom view thereof.

The broken lines in the drawings are included to show portions of the growing enclosure that form no part of the claimed design.

1 Claim, 9 Drawing Sheets(56)
